CLAIM

The ornamental design for satellite speaker, substantially as shown and described.

DESCRIPTION

FIG. 1 is a perspective view of a satellite speaker as seen from the front, top and side;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The dotted line portions of the drawings represent environmental structure only and form no part of the claimed design.

1 Claim, 4 Drawing Sheets(56)
